US0D1062753S

(12) **United States Design Patent** (10) **Patent No.:** **US D1,062,753 S**
(45) **Date of Patent:** **** Feb. 18, 2025**

(54) **ADJUSTABLE WRIST PAD**

(71) Applicant: **Jiangmen Yucheng Technology Co., Ltd.**, Jiangmen (CN)

(72) Inventor: **Weicheng Chen**, Jiangmen (CN)

(73) Assignee: **Jiangmen Yucheng Technology Co., Ltd.**, Jiangmen (CN)

(**) Term: **15 Years**

(21) Appl. No.: **29/877,389**

(22) Filed: **Jun. 6, 2023**

(51) **LOC (15) Cl.** **14-99**

(52) **U.S. Cl.**

USPC **D14/460**

(58) **Field of Classification Search**

(57) **CLAIM**

The ornamental design for a adjustable wrist pad, as shown and described.

DESCRIPTION

FIG. 1 is a front perspective view of a adjustable wrist pad, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a usage state view thereof.

The broken lines in the drawings illustrate the portions of the adjustable wrist pad, which form no part of the claimed design.

1 Claim, 8 Drawing Sheets
